[57] CLAIM

The ornamental design for golf mat, as shown and described.

DESCRIPTION

FIG. 1 is a perspective view of a golf mat embodying my new design;

FIG. 2 is a top plan view thereof;

FIG. 3 is a bottom plan view thereof; and,

FIG. 4 is a side elevational view thereof, the other side views being identical.

The broken line showing in FIG. 1 is for illustrative purposes only.

FIG. 1

FIG. 4
